CURRENT RESPONSIVE ACCELERATION
CONTROL FOR ELECTRIC MOTORS

Emilio Battilana, Genoa-Cornigliano, Italy, assignor, by mesme assignments, to Soc. Per Azioni Stabilimenti Elettromeccanici Riuniti Ansaldi San Giorgio, Genoa, Italy, a company of Italy

Application February 16, 1949, Serial No. 76,674
In Italy February 23, 1948

4 Claims. (Cl. 318—394)

1

In an electric traction equipment, the manner of producing the sequence of remote control switchings, called telerupters, for cutting out resistances is well known, as effected by means of an auxiliary motor which drives a cylinder controlling in turn the remote switches and of a relay, called acceleration relay, which for a given value of current is set into a certain operative position and, responsive to the opening of electric circuits, stops the auxiliary motor and consequently the sequence of remote control switching.

During the starting period of the motor, the current therethrough is reduced and thereby the acceleration relay is caused to take another operative position which, as a result of electric circuit connections, sets the auxiliary motor in motion again, thereby closing the sequence of the remote control switching for starting again.

Sometimes it is desirable to assign several calibrations to the acceleration relay and therefore it happens that during the starting operation, in passing from one calibration value to another, there is no gradual passage between the two or more values of the acceleration relating to the two or more values of calibration current.

Accordingly, it is an object of the present invention to eliminate this drawback and to enable the accomplishment of a starting which graduates the increase in acceleration between certain limits.

A further and more particular object is to enable a starting having a constant variation of acceleration as a function of time.

In the sheet of drawings having a single figure hereto annexed there is illustrated, only by way of example, an embodiment of a device according to the present invention.

The device here disclosed in effect very advantageously substitutes for the said auxiliary motor, the control cylinder and the acceleration relay and the several calibrations as known.

Referring to the drawing, which is a circuit diagram, there is shown an acceleration relay having two connected magnetic circuits constituted by cores 111, 112 and 113, the yoke 114 and armature 115 slightly biased by spring 116 in the position shown in the figure. Said armature oscillating on core 112 operates the closing and opening of contacts 117 and 118 alternatively. On the cores 111 and 113, there are two copper tubes, 119 and 120, constituting two short-circuit windings which serve to delay the release of armature 115 by a predetermined and constant time value. The voltage coil 121 acts to generate a magnetic flux in the circuit composed by cores

2

111 and 112 closed by yoke 114 and the armature 115. Coil 122 acts similarly respecting the circuit composed by cores 112, 113, yoke 114 and armature 115.

5 Coil 123 through which the traction current passes, has the function of generating a magnetic flux in both circuits, one circuit including elements 111, 115, 112 and 114, and the other including elements 112, 115, 113 and 114. In these 10 magnetic circuits there will circulate two fluxes of widely different values, owing to the differences in the values of their respective reluctances. If the armature be considered in the position shown in the figure and the coil 121 be fed, if now this 15 feeding be interrupted and the voltage coil 122 be fed, core 113 may attract armature 115 only after the retardation time caused by tube 119 has elapsed, if the current value in current coil 123 will have such a value as to allow it, because the 20 flux generated by this coil will prevailingly circulate in the circuit consisting of elements 112, 115, 111 and 114 which will be opposed to the armature motion. The result is that the armature oscillations are under the control of the 25 traction current and, therefore, of the car load. The stabilization of the current increase is of importance in the operation of the subdivisions of the starting resistance 124.

The reaction moment caused by spring 116 has 30 a negligible value, especially because there is a change of sign when core 111 attracts the armature, which gives rise to a slight inequality of time in the oscillation of the armature.

Consider now the description of the starting of 35 a trackless trolley car, the equipment of which is constituted by a continuous current traction motor 126 with series excitation 125, a starting resistance 124, control apparatus 111—123, a remote control line switch 1, to which corresponds 40 contacts 11, 12 and 13, a set of remote control sequence switches 2—9 wherein for switch 2 there corresponds contacts 21—26, for switch 3 there corresponds contacts 31—36, and so on. Said set of remote control switches is divided into two 45 groups which are operated by cross-coupled contacts in connection with feeding and locking of coils 121 and 122 alternatively. The main operating organ is the pedal which as shown in the diagram is represented by contacts 0 to IX. Said 50 pedal has the following positions:

State of rest, by which all circuits are open;
First position, by which the motor runs on resistance 124;
II to IX positions, by which the exclusion of 55 the starting resistance takes place.

Starting of the car

In the first position of the pedal, it closes contact I thereby feeding the remote control switch I of the line; the latter closes contacts 11 and 12 putting motor 126 in circuit with the network, and closes contact 13 preconditioning the feeding of remote control switch 2. Motor 126 starts through the whole series resistance 124.

Suppose now the case in which the pedal is put directly into the IX position and contacts 0 and II to IX are closed; contacts II to IX precondition the circuit for the feeding of remote control switches 2—9.

By closing contacts with 0, coil 122 is fed and core 113 will be able to attract armature 115 only when the traction current in coil 123 is equal to, or smaller than, the calibration value.

When core 113 is able to attract armature 115, contact 118 will close and feed remote switch 2; the latter operating closes contact 21 excluding a portion of the starting resistance 124, it opens contact 24 and closes contact 25 feeding itself therethrough, it closes contact 26 reconditioning the circuit to feed remote switch 3, it opens contact 22 interrupting the feeding to coil 122, it closes contact 23 thereby feeding coil 121. If, by the exclusion of the portion of the starting resistance 124, a rush of current is produced in the traction circuit and, therefore, in coil 123, which is of a higher value than that of the calibration of the device, it will have the result of holding armature 115 in contact with the core 113; when said rush of current shall have fallen to the calibration value, armature 115 will be released by core 113 and attracted by core 111; this, however, will happen if the rush of current shall have the same or a longer duration than the retardation produced by popper tube 120; otherwise, this time will prevail over the first mentioned time; to insure that the traction current be established sooner than the current in coils 121 and 122, a suitable arrangement of contacts of the remote switches is provided. When armature 115 has been released by core 113 and attracted by core 111, contact 118 will open and nothing will happen, because switch 2 has been locked up through contact 25; contact 117 will close and feed remote control switch 3; this switch 3 will close some of its contacts and open others in accordance with the analogous function of these contacts in case of remote control switch 2. This will be repeated for remote switches 4—9, while armature 115 will continue to oscillate with a minimum time period equal either to the retardation caused by the copper tube 119 and 129, or to the duration of the rushes of traction current produced by the exclusion of the portions of starting resistance 124.

By the feeding of remote control switch 9, the exclusion of starting resistance 124 is brought to an end and contact 92 is open; the armature oscillations are definitely stopped, for contact 82 has been already opened by remote control switch 8 and the starting operation may be considered ended.

If the pedal had not been pushed all the way down, but, for instance, only so far as to close contact IV, the exclusion of resistance 124 would have stopped with the closing of remote switch 4, because remote control switches 5—9 are operated by contacts V to IX which are still open. The armature has stopped at the position illustrated in the figure, because remote switch 4 has opened contact 42 and closed contact 43; in

due course, 411 will have attracted armature 115 and, consequently, contact 117 has been closed; but the latter cannot feed remote switch 5 because contact V is open. By pushing the pedal still farther, the already described sequence will be resumed, with the possibility of stopping at any predetermined position.

Stoppage of car

1r By bringing the pedal from position IX to that of rest, contacts IX to I in decreasing order are opened, while contact 0 opens together with contact 2, so that the restoration of remote switches 9 to 1 takes place by steps, thereby putting the starting resistance 124 into circuit as far as the opening of remote line switch I which breaks the feeding of traction motor 126. During the restoration of remote switches 9—1, armature 115 oscillates while following them, although it is not connected, and it could even lose some cycles. If when letting the pedal come back it is stopped in an intermediate position, motor 126 will go on running with the corresponding portion of resistance left in circuit; furthermore, it will be readily understood that armature 115 has been placed in such a position that the renewal of a starting operation is possible by pushing the pedal instead of drawing it back.

Braking of the car

The control device for braking operates in a similar manner to that of the starting; for the sake of simplicity the arrangement as disclosed has not been provided with the apparatus comprising the braking circuit.

Although for descriptive reasons, the present invention is based on what has been shown and described by way of example, it is obvious that many modifications and additions may be included in the embodiment of the invention, all of them nevertheless being based on the fundamental principles of the invention, as defined in the appended claims.

Having now particularly described and ascertained the nature of my said invention and in what manner the same is to be performed, I declare that what I claim is:

1. In an oscillatory device for controlling the starting of electric motors, the combination of 50 a control circuit having two series of control devices inserted therein, each said control device having two contact elements, a bar of magnetic material mounted for oscillatory movement about a pivot, a contact carried by each end of the bar, respective cooperative contact plates each having circuit connections to one of the contact elements of one series of control devices for said starting, a magnetic bridge the two ends of which are located in operative relation to the respective ends of said bar, like voltage coils carried on each of said bridge ends respectively, one end of the two coils being connected to one pole of the feeding line of the motor and of the control circuit, the other ends of said coils being connected to other contact elements of said control devices and thereby to the other pole of said feeding line.

2. A device according to claim 1, wherein the 70 said magnetic bridge is E-shaped and includes a central core, the upper end of which is magnetically connected to the said magnetic bar at said pivot, said central part having a current coil in series with the motor circuit.

3. A device according to claim 2, wherein the 75 respective extreme ends of said magnetic bridge

have short-circuiting sleeves and the said current coils are so energized that each causes the flux in the same direction in the central core.

4. A device according to claim 1, including a tensile spring connected at one of its ends to a fixed point and at its other end to the oscillatory magnetic bar at a point distant from said pivot.
